UNITED STATES PATENT OFFICE.

CHARLES M. STAFFORD, OF MINNEAPOLIS, MINNESOTA.

SILO.

1,380,821.

Specification of Letters Patent. Patented Feb. 17, 1920.

Application filed September 1, 1917. Serial No. 189,248.

To all whom it may concern:

Be it known that I, CHARLES M. STAFFORD, a citizen of the United States, residing at Minneapolis, in the county of Hennepin and State of Minnesota, have invented certain new and useful Improvements in Silos; and I do hereby declare the following to be a full, clear, and exact description of the invention, such as will enable others skilled in the art to which it appertains to make and use the same.

My invention has for its object to provide an improved wall structure, the term "wall structure" being used in a very broad and liberal sense to include such structures as roofs and arches; and to such ends, generally stated, the invention consists of the novel devices and combinations of devices hereinafter described and defined in the claims.

Stated more definitely, the invention has for its object to provide a so-called wall construction which may be very cheaply constructed and erected, from lumber, such as 2x4's that are of such short lengths that they have very little commercial value. For instance, it is a custom for saw mills to discard 2x4's that are 4 feet and less in length, as lumber, and to use the same as fuel. In some instances these short pieces have been used for commercial purposes other than fuel, but they always have a relatively low commercial value as compared with longer lengths.

A wall structure of the kind involving my invention is particularly adapted for use in the construction of silos, grain bins, and the like, but as indicated, has great utility in a much more extensive field.

In the accompanying drawings which illustrate several applications or embodiments of my invention, like characters indicate like parts throughout the several views. Referring to the drawings,

Figure 1 is a plan view showing a polygonal silo embodying my invention, the roof thereof being omitted;

Fig. 2 is a fragmentary perspective view of the silo shown in Fig. 1, several of the wall forming elements being loosely shown at random, laid upon the concrete floor of the structure;

Fig. 3 is a detail in perspective showing a portion of the concrete base and one section of one of the so-called anchor rods;

Fig. 4 is a perspective view showing the

so-called wall structure used as a roof or trussed arch;

Fig. 5 is a fragmentary perspective illustrating the manner in which the wall of a silo, or the like, may be built up in sections, and the sections assembled, as entireties;

Fig. 6 is a transverse vertical section taken on the line 9—9 of Fig. 5; and

Fig. 7 is a view corresponding to Fig. 6, but illustrating a slightly modified construction.

Referring first to the construction illustrated in Figs. 1, 2 and 3, the numeral 11 indicates a concrete base and the numeral 12 indicates so-called anchor rods, the lower ends of which are embedded in the concrete base. The wall is a polygonal structure in which the wall forming timbers extend on the chords of an arc that circumscribes the wall structure; and the so-called anchor rods 12 are arranged in groups of three at the angles of the wall structure. The anchor rods 12 may be of different construction and arrangement, but advisably, they are made of half round pieces, towit with lapped joints, so that they may be built up to any desired height in the process of erection, and after the lower sections have been embedded in the concrete base at their lower ends.

In the construction of silos and various other structures which require close solid walls, the improved wall structure is made up of relatively long timbers 13 and relatively short timbers 14. In the larger silos, the so-called long timbers 13 will usually have a length of about four feet, while the so-called short timbers 14 will be of less length, and the difference in the length between the timbers 13 and 14 will vary, depending upon how many of the longer timbers are employed for any particular silo or other structure, and the angles at which the long timbers are set, relative to each other, on the chords of the circle described about the common center of the silo or other structure, but, in all cases, the shorter timbers 14 will be of considerable less length than the long timbers and of the proper length to fill the space between the alternate members of the long timbers in the same course.

The wall is built up in horizontal layers and each layer consists of the long and short timbers alternately positioned, circumferentially, and all of the said timbers are provided with perforations which adapt

them to be strung or slipped onto the said rods, in the arrangement illustrated in the drawings. The ends of the short timbers 14 are beveled so that they closely fit 5 the abutting inner edges of the horizontally alined long timbers 13, and the outer ends of the long timbers are beveled so that they lie in the plane of the outer surfaces or edges of the said short sections 14. Inasmuch as 10 the wall structure will have many sides, to-wit, more than four sides, it follows that the connected wall sections will stand at an obtuse angle to each other, and consequently, that the abutting long and short timbers will 15 have an overlap that is much greater than the horizontal width of the timbers. In Fig. 2, the rod receiving perforations in the loose timbers 13 and 14 are indicated, respectively at 13^a and 14^a. Not only are the long and 20 short timbers 13 and 14 alternately arranged circumferentially in the same horizontal layer or course, but the long timbers 13 are alternated with the short timbers 14 vertically in the adjacent courses, so that the ends 25 of the long timbers 13 of the one course overlap with the ends of the long timbers of the next lower and next higher course. This gives a strong joint connection in which, when the overlapped ends are firmly united, 30 a strong trussed structure is produced. In the arrangement shown in Figs. 1, 2 and 3, the corner groups of three rods are located, one at the angle and one at each side of the angle. Otherwise, stated, the central members 35 of each group are passed through the overlapped ends of the long timbers 13, while the side members are passed through the alternately laid long and short timbers. The beveled ends of the short timbers, by 40 close engagement with the inner edges of the long timbers, form bases which positively prevent buckling of the connected wall sections on the central rods 12 as a hinge. Of course, all buckling action may be further 45 prevented by nailing together the overlapped ends of the long timbers when desired.

With the arrangement of the built-up rods 12 illustrated in Fig. 3, the rods may be extended to any desired height, step by step, as the wall structure is built up. Preferably, the connection between the rods and perforations in the timbers will be loose so that the timbers of the wall will be free to 55 expand when moist and under their own weight alone, or the added weight of the roof structure, will settle when dry, and thus avoid formation of open joints; and for this reason, in many structures, the use of nails 60 is advisably entirely avoided, because nails interfere with the settling of the timbers after expansion and subsequent contraction.

The so-called roof or trussed arch structure shown in Fig. 4, may be assumed to be 65 built up on the same plan as the structure

illustrated in Figs. 1, 2 and 3, except, of course, that it does not form a complete circle, but is somewhat less than a semi-circle, and hence, the timbers and rods of this structure are indicated by the same numerals that are used on the corresponding parts in Figs. 1, 2 and 3. The structure shown in Fig. 4 is assumed to be the roof of a building, and hence, one end wall thereof is indicated by the numeral 15. The same 70 trussed arch structure shown in Fig. 4 is capable of being used in many different ways, either singly or in plural arrangement. For example, in forming a bridge structure, a series of these arches might be employed to 80 support the bridge floor structure.

The so-called wall structure, instead of forming a complete wall, might form only portions, such as the spacing rings or hoops of a wall structure made up thereof and of 85 boards nailed thereto, either inside or outside or both.

In the several wall structures so far described, the process of erection has been assumed to be by laying the timbers in courses, 90 but Figs. 5, 6 and 7 illustrate how a wall structure, such as that shown in Figs. 1 and 2, may be built up on the ground or on a bench, in sections, and the sections erected and assembled as entireties. Fig. 5, for example, shows two erected sections and one section still lying flat on the concrete base 11. In this method of erection, it is not feasible to anchor the lower ends of the rods in the concrete in advance of the erection of 100 the sections. If similar anchoring or connecting rods are employed, they should be passed through the proper perforations before the sections are erected; and in Fig. 6, such rods are indicated at 12^a. In Fig. 7, the 105 long and short timbers are shown as connected by nails 18.

In the construction of walls in silos and other buildings in accordance with my invention, such structures are provided with 110 many sides, to-wit, always more than four, and preferably so many sides that the wall approximates, in a general way, a cylindrical wall. The advantages of this are many. In the first place, it is necessary 115 in order to use short lumber or timbers, and in the second place, it arranges to connect sides at obtuse angles on the lines of short chords of approximately cylindrical structure, and this gives a long lap to the overlapped ends of the long timbers and, moreover, provides an arrangement in which the beveled or obliquely cut ends of the short timbers afford good braces for preventing angular movements of the sides of 120 the wall. Thus a well trussed structure that will not collapse is produced in a very 125 simple and cheap manner.

From the standpoint of economy, the advantage in being able to use commercially 130

the short timbers of two different lengths can scarcely be overstated. It is a well known fact that the Pacific Coast region is the chief source of the lumber supply for 5 the United States and Canada, at the present time, and the shortest listed commercial length from the principal Pacific Coast mills has hitherto been six feet. The shorter lengths, as a rule, have simply been allowed 10 to go to waste, being run to the burner or so-called "hell-hole" and burned up. In the more thickly populated central or Eastern States, comparatively little lumber is cut, at the present time, and, in some instances, 15 some of the shorter cuts of four or five feet in length have been used for boxes or for fuel. So far as I know, however, I am the first to design any commercial structure in large demand, such as silos, wherein these 20 shorter cuts from the big mills can be, and would naturally be employed, in an extensive way, sufficient to establish these short cuts as commercial lumber. This is particularly true in respect to the shorter of 25 the two lengths of the cuts employed in my above disclosed structure. Silos are now used not only to store green food for cattle and hogs, but for fowl; and hence, they range greatly in size. They are practically 30 always cylindrical, or approximately cylindrical, but vary greatly in diameter and in height. The cattle or stock food silos usually run from about ten to eighteen feet in diameter, but the small or so-called 35 "chicken" silos usually run from about four to eight feet in diameter. My structure is also adapted for use as a water or other liquid tank, and, of course, such tanks are made of a great diversity of diameters. 40 When the silos or tanks are of the relatively small diameters, above noted, the longer of the two timbers would not exceed two or three feet and the shorter might not exceed one or two feet. 45 From the foregoing, it will be seen that my invention provides a commercial structure, which will utilize as lumber practically all of the short cuts from the big mills, which have hitherto gone to waste; 50 and it further follows that this short cut lumber can be had at a lower price, thus enabling silos and tanks to be available to the farmer at a much lower cost. My invention, therefore, effects a radical improvement 55 in this art of great commercial value, especially at this particular time, when such

great efforts are being made to maximize the food products from the land.

What I claim is:

1. The combination with a suitable base, 60 of a substantially cylindrical wall structure having more than four sides set about a common center, at obtuse angles in respect to each other and composed of a plurality of layers or courses of timbers of two different lengths alternated in each circumferential layer or course and also alternated vertically in the successive courses, with the long timbers overlapped at both of their opposite meeting ends and the short timbers 70 having beveled ends disposed to fill the spaces between the long timbers with their beveled ends bearing against the inner faces of the long timbers, and rods anchored in said base at the meeting angles of the chords 75 of the arc and passing through perforations in all the overlapped ends of the long timbers thus always connecting the same with freedom to rise or fall thereon to compensate for expansion and contraction. 80

2. The combination with a suitable base, of a substantially cylindrical wall structure having more than four sides set about a common center, at obtuse angles in respect to each other and composed of a plurality of 85 layers or courses of timbers of two different lengths alternated in each circumferential layer or course and also alternated vertically in the successive courses, with the long timbers overlapped at both of their opposite meeting ends and the short timbers having beveled ends disposed to fill the spaces between the long timbers with their beveled ends bearing against the inner faces of the long timbers, rods anchored in said base 95 at the meeting angles of the chords of the arc and passing through perforations in all the overlapped ends of the long timbers, and other rods anchored in said base and passing through perforations in all of the 100 long and all of the short timbers, whereby said elements are all interlocked with freedom for the timbers to rise and fall to compensate for expansion and contraction, substantially as described. 105

In testimony whereof I affix my signature in presence of two witnesses.

CHARLES M. STAFFORD.
